UNITED STATES PATENT OFFICE.

XAVER BOSSART, OF PATERSON, NEW JERSEY, ASSIGNOR TO AMERICAN SILK THREAD FINISHING CO., OF PATERSON, NEW JERSEY, A CORPORATION OF NEW JERSEY.

SILK-THREAD-FINISHING MACHINE.

No. 873,491.

Specification of Letters Patent.

Patented Dec. 10, 1907.

Original application filed March 22, 1905, Serial No. 251,442. Divided and this application filed March 13, 1906. Serial No. 305,920.

To all whom it may concern:

Be it known that I, XAVER BOSSART, a citizen of the Republic of Switzerland, residing in Paterson, county of Passaic, and State of New Jersey, have invented certain new and useful Improvements in Silk-Thread-Finishing Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to apparatus for finishing, lustering and winding silk and other textile filaments, and it has for its object to improve on apparatus of this nature at present in use with a view to increasing the efficiency of the apparatus and to bringing out better results in the quality of the product.

To this end, my invention consists in the improved means for treating the filaments to finish and luster the same, as well as in the several novel features and certain combinations and arrangements thereof.

Referring to the drawings, Figure 1 is a side elevation of the finishing and lustering means; Fig. 2 is a plan view of said finishing and lustering means, and, Figs. 3 and 4 are views illustrating certain modifications.

d' is a suitable support on which rests a steam-chest *d*².

*d*² designates brackets carrying a receptacle *d*⁴ which is divided into two compartments by a partition *d*⁵; the receptacle may be adjusted vertically by nuts *e*¹ screwed onto threaded stems *e*² which support blocks *e*³, *e*⁴ on which the receptacle *d*⁴ directly rests. The threads, being drawn longitudinally by some suitable known means are led from their supply through eyelets *e*⁵ on the block *e*³, then down under a rod *f*¹, which rests in sockets *f*² below the level of a suitable liquid in the receptacle, then through a reed *f*³, then over a sponge *f*⁴ disposed in a trough *f*⁵ on partition *d*⁵, then over a rod *g*¹ covered with felt *g*² or other absorbent material, then through another reed *g*³. (Not shown in Fig. 2). The threads are thus caused to take up some of the solution, the superfluous portion of which is afterward

successively removed by the sponge *f*⁴ and felt covered rod *g*¹. The trough *f*⁵ is perforated as at *g*⁴, so that the portion of the solution which is wiped off by the sponge and collects in the trough runs into a different compartment of receptacle *d*⁴ from that in which the solution is primarily placed. After passing through reed *g*³, the threads extend over a steam-chest *g*⁵ which is perforated at the top (Fig. 2) so that live steam moistens the threads. Such moistening may have different effects, according to the nature of the solution used; in the adaptation shown it is intended to assist in the removal of more of the superfluous solution clinging to the threads by softening it, such superfluous portion of the solution being taken up by an absorbent belt *h*¹ which is passed around the steam-chest *g*⁵ and dips into a vessel *h*² containing water or other cleaning solution. From time to time, as the belt becomes laden with the solution, it may be advanced on the steam-chest *g*⁵ to present a fresh surface to the threads.

In Figs. 3 and 4 modified constructions of the mechanisms of Figs. 1 and 2 are shown. The receptacle *d*⁴, its supporting means *d*³, *e*¹, *e*², *e*³ and *e*⁴, thread guides *e*⁵, reed *f*³ and guide-rod *f*⁴ are or may be all as in Figs. 1 and 2. In this instance, however, after the threads leave the solution they pass over a brush *h*¹⁰ arranged in the receptacle, whereby some of the adhering solution is removed from the threads; the threads then pass over the perforated steam-chest *g*⁵ carrying the absorbent strip *h*¹. Between this and the steam-chest *d*² is arranged another unperforated steam-chest *h*¹¹ over which is extended an endless strip *h*¹² of absorbent material which may be kept taut by a roller or other weight *h*¹³. Or, a roll *h*¹⁴ of the strip of absorbent material may be supported in bearings *h*¹⁵ on the supports *d*³, the free end portion of the strip being laid over the steam-chest *h*¹¹.

From time to time as either strip *h*¹ or *h*¹² becomes charged with the solution collected thereon it may be advanced to present a fresh surface to the threads.

*h*³ is a felt pad on chest *d*² over which the threads next pass, and *h*⁴ is a removable plate of copper or some such metal affected by

heat differently from the metal of the steam-chest and set in a recess h^5 of the steam-chest. One purpose of the steam-chest g^5 , and the devices h^3 and h^4 is to gradually heat the threads on their way from the bath to the top surface of the steam-chest d^2 , over which they finally pass, so that they are not subjected to a shock of a sudden change of temperature. I may in some instances also employ the removable plates i^8 seen in Figs. 3 and 4, the same being set in the recess h^5 in spaced relation, a glass bar i^9 being laid on the threads between them to keep the threads in contact therewith, if desired.

For some purposes, according to the solution used, it may be desirable to moisten the threads after they leave the steam-chest d^2 . For this purpose, another perforated steam-chest g^5 and belt h' , may be placed at the farther end of the steam-chest, as seen in Fig. 2. i^2 denotes the piping by which the steam-chests are supplied with steam.

As the threads are not intended to engage the steam-chest g^5 in case the belt h' is not used, the receptacle d^4 may be adjusted vertically so that the threads fully clear the steam-chest.

It will be understood that the parts g^5 and h' operate as well as the parts h^3 and h^4 to make the rise in temperature of the threads gradual as the threads proceed from the solution-containing receptacle to the point where they receive the highest heat effects from the steam-chest. But this is not the only function of parts g^5 and h' ; these parts, by subjecting the threads to heat and moisture (in the form of steam) at a point intermediate that where the threads take up the solution and that where they receive the highest heat effects from the table, make the solution on the threads take a more regular character and a smoother condition than it has as it comes from the receptacle before it can dry on contact with the steam chest, so that any tendency for the solution to dry on the threads in globules or other irregular form, tending to make the threads uneven and rough as heretofore, is prevented.

The plate h^4 (i^7 or i^8) is removable so as to be adapted to be taken out from time to time to be cleaned as the solution cakes and dries thereon and hampers the operation by catching the threads and breaking them and otherwise interfering with their free progress over the table.

My present application is a division of my application filed March 22, 1905, Serial Number 251,442; I therefore make no claims herein to the use of means for heating and simultaneously moistening the threads, or an absorber, in combination with a solution applying means and a heated thread contact medium, broader than those hereinafter set forth,

such broader claims being contained in the application aforesaid. Nor do I make claims herein to the use of a removable metallic portion in connection with the heated metallic thread contact medium broader than those hereinafter set forth, such broader claims being contained in an application filed by me August 22, 1905, Serial Number 275,245.

Having thus fully described my invention, what I claim as new and desire to secure by Letters Patent is:

1. In a machine for finishing and lustering textile filaments or the like, a heated metallic body having a contact surface for the filaments, the contact surface portion of said body having one part thereof composed of one metal and another part thereof composed of a metal affected by heat differently from said first-named part, substantially as described.

2. In a machine for finishing and lustering textile filaments or the like, a heated metallic body having a contact surface for the filaments, the contact surface portion of said body having one part thereof composed of one metal and another part thereof removable and composed of a metal affected by heat differently from said first-named part, substantially as described.

3. In a machine for finishing and lustering textile filaments, or the like, a metallic table having a recess in its top or acting surface and a metallic plate removably arranged in said recess and composed of a metal affected by heat differently from the metal of the table, substantially as described.

4. In a machine for finishing and lustering textile filaments or the like, a metallic table having a recess in its top or acting surface, spaced removable plates arranged in said recess transversely of the table, and means arranged between said plates for maintaining the threads in contact with both of said plates, substantially as described.

5. The combination of a suitable support, means for treating the threads in a suitable solution, a heated thread contact surface, a heated support arranged relatively between said means and said surface, and a flexible strip laid over and hanging pendent from the support and adapted to be engaged by the thread, substantially as described.

6. The combination of a suitable support, means for treating the threads in a suitable solution, a heated thread-contact surface, a perforated steam chest located between said solution treating means and said heated surface, an absorptive belt extending over said steam-chest, and a belt-cleaning means, substantially as described.

7. The combination of a suitable support, means for treating the threads in a suitable solution, a heated thread-contact surface, a

perforated steam chest located between said solution treating means and said heated surface, an absorptive belt extending over said steam-chest, and a vessel for containing a belt cleaning medium, said belt extending into said vessel, substantially as described.

In testimony, that I claim the foregoing, I

have hereunto set my hand this 9th day of March, 1906.

XAVER BOSSART.
